UNITED STATES PATENT OFFICE

HERBERT R. STRATFORD, OF CLEVELAND, OHIO, ASSIGNOR TO THE STRATMORE COMPANY, OF CLEVELAND, OHIO, A CORPORATION OF OHIO.

METHOD OF SURFACING.

Application filed April 12, 1926. Serial No. 101,450.

The present invention, relating, as indicated, to methods of surfacing, is directed to a new and improved method for operating upon various surfaces, such as those of wood, 5 steel and metal plates or panels for the purpose of either bringing the entire surface to a level condition or to remove material at certain points, or for the purpose of smoothing and rubbing down the surface, as for 10 example in the case of coated surfaces where the coating is a paint, varnish, lacquer or other material. The principal object of the 15 present invention is the provision of a method and apparatus for surfacing materials without the objections which have been met 20 with heretofore, which consist in difficulties experienced in first applying the tool to the work without producing marring of the surface by the edge or side of the surfacing 25 element and without permitting the surfacing element to operate relatively intermittently, that is, by apparent "jumps" from one portion of the surface to the other as is 30 the case where a rotating surfacing disc is held flat against a relatively flat surface. 35 To the accomplishment of the foregoing and related ends, said invention, then, consists of the means hereinafter fully described and particularly pointed out in the claims.

The annexed drawings and the following description set forth in detail certain means and one mode of carrying out the invention, such disclosed means and mode illustrating, however, but one of various ways in which 35 the principle of the invention may be used.

In said annexed drawings:

Fig. 1 is a side elevation of one form of my improved apparatus; Fig. 2 is a central transverse section through the surfacing 40 element and supporting means therefor; Fig. 3 is an edge view of the abrasive and supporting elements shown in Fig. 2 representing the same in action; Fig. 4 is a partial transverse central section through another type of abrasive disk and supporting 45 means, etc.; Fig. 5 is an edge view of the means shown in Fig. 4 when in operation; Fig. 6 is a transverse sectional view of a modified form of my apparatus.

Numerous methods and apparatus have 50 been employed for the purpose of removing material from surfaces or for the rubbing or smoothing of surfaces in which a surfacing element was secured to an operating shaft or a reciprocating or moving element.

All such methods and apparatus may for convenient description be divided into two general devices, the first, that in which the apparatus, and particularly the surfacing element, is larger than the work on which it 60 is employed and in which the work is of such a size that it can be brought to the apparatus, and second, that in which the work is stationary or of such area that it exceeds very considerably the area of the surfacing 65 element employed. In the first division fall all such abrasive and surfacing tools as are at present in any general use, including shoe surfacing machinery, in which the shoe, or a portion thereof, is pressed into a moving 70 but fixed tool carrying an abrasive surface. The problem of operating upon such articles is an extremely simple one, as only small portions of the surface of the article are operated upon at one time, and the article, 75 by reason of its small size can be readily handled and applied to the surfacing element.

It is in the second division of such methods and apparatus that great difficulty has 80 been experienced, particularly on certain types of surfaces, such for example as metal, wood and coated surfaces where a dead smooth, or level, or uniform surface is required, by reason of the inability of an 85 operator to hold against the surface being operated on, a rapidly moving surfacing element, such as a sheet of abrasive material secured to a block, pad, foot, shaft or belt, as the case might be. For illustration we 90 may consider the case of a rapidly rotated disk of abrasive which is mounted transversely on the end of a rotating shaft provided with suitable handles held by the operator and pressed steadily against a surface. It will be evident that such a rapidly rotating disk will exert a very considerable torque tending to rotate the entire shaft and the handles, and this torque must be resisted 95 by the operator. The heavier the work the 100 higher the torque and the greater force which is required to be exerted by the operator to maintain the machine flat against the work. As a matter of fact it has been found absolutely impossible for the ordinary workman to maintain such a surfacing element in proper relation to the work, that is, flat against the work and with an equal pressure applied all over the disk. 105 The result of the least inequality in pressure 110

between various areas or portions of the disk is to cause the machine to move suddenly over the work and to jump, producing a deeper cut at the point where the machine 5 lands than elsewhere, which appears in the finished surface as a scallop or slightly recessed portion, which is at once discernible, particularly when the surface is subsequently coated with paint, varnish, or 10 some similar material.

The difficulties of operation referred to above can best be understood by comparison of the present apparatus with a perfectly solid, rigid wheel. If a solid abrasive wheel 15 be applied flat to a flat surface, it will not cut smoothly and uniformly as can be at once determined by the sound of the wheel in passing over the work. The sound is that of an intermittent action and an operator 20 holding such wheel can also feel this interrupted cutting which apparently comes from the jumping of the wheel from one portion of the surface to another. If such a wheel be applied to the work in any way except flat, 25 the edge of the wheel will, of course, first strike the work and will cut into it even though the wheel be shifted at once and moved to a position in which it is flat. On anything except flat work a wheel will, of 30 course, have only a single line of contact when passing over or around a surface, for example, and cannot operate against convex surfaces at all.

In my United States Patent No. 1,558,714, 35 I have discussed one method of surfacing which avoids the difficulties referred to above, and I have found a second method by which these objectionable results can be avoided and a true, uniform surface can be 40 secured on a sheet or panel of metal, wood, or other material.

My present invention, briefly stated, consists in applying to a panel to be surfaced a rapidly moving sheet of suitable surfacing 45 material, such as a disk or sheet of abrasive, which is supported by either a slightly compressible and slightly bendable support, or a support which has a substantial compressibility which serves the same purpose as the 50 flexibility or the bending present in the first-named type of support, and then applying a surfacing element so supported to a surface to be operated upon with a pressure which is greater on one portion of the disk 55 than on the remainder in order to slightly tilt the normal plane of the surfacing element with respect to the plane of the surface being operated upon. If a support which is both compressible and bendable, or flexible, 60 is used, then this excess pressure on one portion of the disk will both compress the support and bend it slightly out of the normal plane of the disk. If a purely compressible support is employed the excess pressure will 65 compress this support and this portion will

permit the uncompressed or remaining portion of the support to lie at a slight angle to the plane of the work. In either case only one portion of the surfacing disk is actually applied against the work with any such force 70 as to cause abrasion thereof, with the result that the operator can very much more readily control the position and use of the device and there is no danger of the disk jumping over the work since it is in inoperative contact with the work except over a portion of its surface, all of which lies on one side of the center of the disk. 75

It is essential in an apparatus of the character I have already referred to and which is now being described, to employ in the operating elements, that is in the train of elements which include the support, the compressible or flexible pad and the surfacing disc or sheet, some shock absorbing element 80 which will permit the surfacing element to give slightly when it is first applied to the work, both for the purpose of preventing the edge of the disc from cutting into the work and also for the purpose of continually absorbing the shocks which otherwise are transmitted directly to the shaft and the metal supporting plate and which are the shocks 85 which cause a solid wheel to act interruptedly and to jump on the surface of the work. 90 A third reason for the employment of some shock absorbing material in this train of elements is to permit the abrasive disk to go over a rounded surface and to afford a surface engagement instead of a line engagement in order to properly condition convex surfaces such as rounded panels which are 95 commonly employed in automobile bodies and the like. 100

Referring now to Fig. 1, I have shown an apparatus devised to carry out the present method which consists of a head or frame 1 provided with handles 2 and 3, the handle 2 being hollow and carrying a flexible rotating shaft 4 which may be driven from any suitable source of power, such for example as an electric motor (not shown). The shaft 4 drives, through bevel gears 5 and 6, to a shaft 7 which extends through the bottom of the case 1 and carries adjacent its lower end a series of overlapping relatively rigid plates 8, 9 and 10. Also secured to the shaft is a supporting disk or pad 11 which extends beyond the outer edge of the largest disk 10, this pad being of any suitable material which shall be both slightly compressible and also yieldable or bendable. It will also be understood that the supporting disks 8, 9 and 10 are very slightly yieldable and that the largest of these may, if desired, be extended to the edge of the supporting pad 11, in which case it should also be permitted to flex or bend slightly to permit of bending of the outer portion of the pad 11. Secured to 110 the shaft 7 is a suitable abrasive disk, one 115 120 125 130

method attaching the same being shown in Fig. 2, in which the disk 12 is provided with a recessed central portion 13 having a central opening 14 and a series of radially arranged openings 15, which are engaged by pins 16 carried by a disk 17 which removably engages the end of the shaft 7. Any suitable method of securing the disk to the shaft may be employed or, if desired, the disk may be 10 removably secured to the outer surface of the pad by a suitable adhesive.

In Fig. 1 I have shown a machine as applied to a flat surface 18 representative of a panel of wood, steel or the like. The machine is applied with an extremely slight angle to this surface so that only a portion of the disk, which is less than one-half of the entire area, is in actual contact with the work, the other side 19 of the disk being 20 raised very slightly from off the work by an angle which is extremely slight, but sufficient to prevent actual engagement between this part of the disk. The effect of applying the device to the work in this manner is to 25 slightly compress the material of which the disk is formed, which may be either rubber, closely matted and compressed felt or equivalent material, and also, as the pressure against the work is increased, to slightly 30 bend the disk, particularly through its radial outer portion.

In Fig. 2 the angular displacement of the engaged portion of the supporting disk 11 is shown and is indicated by the angle A. 35 The compression to which this support is subjected during the operation just described is shown in the edge-like view of Fig. 3 and is represented by the space B between the original and compressed lower 40 surfaces of this support.

In Figs. 4 and 5 I have illustrated the action which occurs when carrying out my method with a relatively unyielding metal supporting disk 20, against which is mounted a supporting element or pad 21 having a 45 greater degree of compression than in preceding form. An abrasive disk 22 is of course mounted against the lower surface of the pad 21. When this series of elements 50 are engaged against a panel the support cannot bend because of the unyielding nature of the reinforcing disk 20. It is, however, sufficiently compressible to yield through substantially the same angle as the 55 combined angle or displacement due to the above compression and yielding in the case of the elements shown in Figs. 1, 2 and 3. The result is a compression of the pad 20 which may be measured by the space C in 60 Fig. 5, and as in the preceding case it is sufficient to prevent operating engagement between the opposite side of the disk and the pad.

As already stated, the end which I desire 65 to accomplish and to which the present

method is directed, is to engage only one segment or portion of the rotating disk against the work regardless of how much pressure is applied, provided a greater pressure is applied to one side of the disk than on the other and securing a sufficient yielding of the abrasive disk, either by supporting it by a pad having both compressibility and flexibility, or by a pad having a sufficient degree of compressibility to give an action 75 equivalent to that secured by both compressibility and flexibility.

It is essential in carrying out this method for the surfacing of various sheets or panels to have a shock absorbing element somewhere in the train of surfacing elements, that is, either in the surfacing disc itself or in one or more of the supports for this disc as already described. Any suitable shock absorbing element may be employed, such 80 for example as compact felt, rubber, and in some cases certain leathers which have some compressibility. Where an element is employed having but slight shock absorbing qualities, the effect may be increased as regards the ease of first applying the machine to the work by beveling off the outer edge of the pad 11 as shown in Fig. 6. In this figure the pad 11 is shown as having a 85 curved outer edge 30 and the disc 31, which is supported by this member 11, may then be either employed slightly to conform to the contour of the supporting pad or may be left free of abrasive adjacent its outer edge 90 if unmolded in order to permit this element to be brought against the work without cutting a deep scratch at the instant of application.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:

1. In a method of surfacing, the steps which consist in rapidly rotating an abrasive element fixed at substantially right angles to a rotating shaft, applying the same against the surface to be operated upon with a pressure which is greater upon one half of said surfacing element than on the other, and supporting said surfacing element over its operating portion by a pad to which it is secured at its center but is free elsewhere therefrom, said pad comprising an advance compressible section and a flexible rear section, the compressibility of the advance section permitting yielding to the contour of the surface to be abraded without flexing the rear section, but the compressibility and flexure, one or both, being sufficient 115 to permit one half of the said surfacing ele- 120

ment to remain out of operative engagement with the surface being operated upon.

2. In a method of surfacing, the steps which consist in rapidly rotating an abrasive element fixed at substantially right angles to a rotatable shaft, applying the same against the surface to be operated upon with a pressure which is greater upon one half of said surfacing element than the other, and 10 supporting said surfacing element over its operating portion by a pad to which it is secured at its center but is elsewhere free therefrom, said pad comprising an advance compressible section and a flexure resisting 15 rear section, the compressibility of the advance section permitting yielding to the contour of the surface to be abraded prior to flexure of the rear section, and the compressibility of the forward section being sufficient 20 to permit one half of the surfacing element to remain out of operative engagement with the surface being operated upon.

3. In a surfacing apparatus, the combination of an operating shaft, a disk surfacing 25 element secured thereto, and supporting means for said disk comprising advance and rear sections, the advance section being compressible and permitting yielding to the contour of the surface to be abraded over the 30 portion engaged against said surface, and the rear section consisting of a plate resistant to flexure but permitting flexure substantially all over one half thereof in response to the pressure with which the disk 35 and supporting means are pressed against the surface to be abraded, but such resistance to flexure being greater than that to compression.

4. In a surfacing apparatus, the combination of an operating shaft, a surfacing disk 40 element secured to the end thereof, and

supporting means for said disk element also secured to said shaft adjacent said disk and comprising a compressible advance section directly engaging the rear surface of said disk element and permitting yielding of said disk element to the contour of the surface to be abraded, and a rear section consisting of lapped plates of flexure resistant material permitting slight flexure of said plates following compression of the advance section of said supporting means.

5. In a surfacing apparatus, the combination of an operating shaft, a disk surfacing element secured to the end thereof, and supporting means for said disk element also secured to said shaft and comprising a compressible forward section disposed against the rear surface of said disk element and permitting yielding of the latter to the contour of the surface to be abraded, said section being flat but having a curved edge merging into said flat portion, and a rear section of lapped plates of flexure resistant material permitting slight flexure of such rear section following compression of the forward section upon the application of the apparatus to the surface to be abraded.

6. In surfacing apparatus, the combination of an operating shaft, a surfacing disk secured centrally thereto, and supporting means for said disk comprising advance and rear sections also secured to said shaft adjacent said disk but free from the latter except adjacent said shaft, the advance section of said supporting means being compressible and the rear section being resistant to flexure, and the advance section permitting yielding to the contour of the surface to be abraded prior to flexure of the rear section.

Signed by me this 2nd day of April, 1926.
HERBERT R. STRATFORD.
